DESIGN FOR A REEL

Louis J. Jedlicka, Lakewood, Ohio

Application January 2, 1948, Serial No. 143,525

Term of patent 14 years

(Cl. D49—1)

To all whom it may concern:

Be it known that I, Louis J. Jedlicka, a citizen of the United States, and a resident of Lakewood, Cuyahoga County, Ohio, have invented a new, original, and ornamental Design for a Reel, of which the following is a specification, reference being had to the accompanying drawing, forming a part thereof.

In the drawing:

The side of the device not shown is substantially the same, in reverse, as the one illustrated.

I claim:

The ornamental design for a reel, substantially as shown and described.

LOUIS J. JEDLICKA.
